(57) **CLAIM**

I claim an ornamental design, decorative palm patio heater, as shown and described.

DESCRIPTION

An aesthetically-pleasing design suggestive of a palm tree with overhanging leaves and a trunk has not been considered for a patio heater prior to this application.

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front three-quarters perspective view of a patio heater suggestive of a palm tree, showing the design with the palm apparently growing out of a 'planter box'. The shading on the underside of the leaves indicates curvature and distinguishes the top and bottom sides thereof.

FIG. 2 is a side view. (Left and right sides would be symmetrical.)

FIG. 3 is a back view.

FIG. 4 is a front view.

FIG. 5 is a top view; and,

FIG. 6 is a bottom view.
